CLAIM

The ornamental design for a cover for hand-held electronic game machine, as shown and described.

DESCRIPTION

FIG. 1 is a front, bottom and left perspective view of a cover for hand-held electronic game machine showing our new design;

FIG. 2 is rear, top and right perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof; and,

FIG. 9 is a reference perspective view showing a state that the cover is attached onto a top surface of a hand-held electronic game machine.

The matter shown in FIG. 9 in dotted line configuration is intended to merely illustrate and environmental feature of the designs but that forms no part of the claimed subject matter.
